CLAIM

The ornamental design for device for biological purification of waste water, as shown and described.

DESCRIPTION

FIG. 1 is a perspective view of a device for biological purification of waste water in accordance with my design;

FIG. 2 is a first side view of the device for biological purification of waste water in accordance with my design;

FIG. 3 is a second side view of the device for biological purification of waste water in accordance with my design;

FIG. 4 is a third side view of the device for biological purification of waste water in accordance with my design;

FIG. 5 is a fourth side view of the device for biological purification of waste water in accordance with my design;

FIG. 6 is a top plan view of the device for biological purification of waste water in accordance with my design; and,

FIG. 7 is a bottom plan view of the device for biological purification of waste water in accordance with my design.
